UNITED STATES PATENT OFFICE

RALPH J. MCINERNY AND EUGENE F. WILLIAMS, OF LOS ANGELES, AND HERBERT L. GLAZE, OF SOUTH PASADENA, CALIFORNIA, ASSIGNEES, BY MESNE ASSIGNMENTS, TO MINERALS INCREMENT COMPANY, OF WILMINGTON, DELAWARE, A CORPORATION OF DELAWARE

APPARATUS FOR MANUFACTURING VOLATILE CHLORIDES

Application filed March 19, 1928. Serial No. 262,654.

The reaction between titanium dioxide and dry chlorine gas has been known for many years, and was mentioned by Rose and Wohler as early as 1850. It was found that the presence of carbon speeds up the reaction and causes it to proceed at a lower temperature than is possible with titanium dioxide alone.

One of the objects of our invention is to provide an improved method for carrying out this reaction in apparatus that is resistant to dry chlorine gas at high temperatures. Another object of our invention is to also provide means to separate the iron chloride which is formed during the reaction, iron being always present in some measure in the crude titanium dioxide used for this purpose. It is almost impossible to make a perfect separation of this iron, but by our improved method and apparatus small amounts of iron are not troublesome to handle.

Another object of our invention is to provide an apparatus which is adapted to manufacture volatile chlorides other than titanium, and which can also be adapted to any reaction where two products are formed both vaporous at the reaction temperature, but one of which condenses at a higher temperature than the other.

In order to fully explain our invention, we have shown on the accompanying two sheets of drawings, an apparatus which is practical for carrying out our improved method, which we will now describe.

Figure 1 is a vertical, longitudinal section-al view of an apparatus embodying our invention, taken on line 1—1 of Fig. 4;

Figure 2 is a front end view or elevation of said apparatus;

Figure 3 is a vertical, transverse sectional view taken on line 3—3 of Fig. 1; and

Figure 4 is a vertical, transverse sectional view taken on line 4—4 of Fig. 1.

Referring now in detail to the drawings, 5 designates a furnace, heated with gas as at 6, with a tubular retort 7, made of carborundum, fire clay, or any other suitable material which will resist chlorine at high temperature, and closed at one end, as with a removable head 8, having a pyrometer 9, there-through, and with a pipe 10, having perfora-

tions 10', inserted therethrough, said pipe being made of carborundum, fire clay or other suitable material, with means at 11, for connecting said pipe 10 with a supply of chlorine. Suitable stuffing boxes 12 and 13 are provided 55 for said pyrometer and said perforated chlorine pipe 10. An outlet flue 14, is shown for said furnace.

Said retort 7 is preferably extended through the end of said furnace, and connects 60 with a closed housing 15, made of cast iron or other resistant alloy, with connecting means, as at 16, with suitable packing at 17. A pyrometer 18 is also inserted into said closed housing 15, through suitable stuffing 65 box 19.

In the top of said housing 15, over an outlet 15', is a filter plate 20, with asbestos packing 21, or other suitable packing, at the edges of said filter plate. A cover 22 is secured in 70 place over said filter plate 20, with an outlet 23 at one side thereof, said outlet connecting with a pipe 24, surrounded by a condenser water jacket 25, with inlet and outlet pipes, 26 and 27, respectively, for supplying water 75 thereto. An outer shell 28 is placed over said closed housing 15, and provided with a smoke stack 29, from the top thereof. Gas burners 30, 30, are placed in said shell, under said closed housing 15.

A receiver 31, is provided, connected with the pipe 24, said receiver having a draw-off cock 32. Connected with the top of said receiver 31, is a reflux condenser pipe 33, with water jacket 34, with inlet and outlet pipes 35 and 36, respectively.

Within the retort 7 is shown a quantity of reaction mixture, designated 37. This can be supplied to the open end of said retort 7, after removing the door or wall 15', of the expansion chamber housing 15, by removing the bolts 38, 38.

The chlorine distribution pipes 10, 10, perforated on their under sides at 10', are covered with the reaction mixture 37, that is, with a mixture of titanium dioxide and carbon, and the chlorine is thus introduced into said mixture. The expansion chamber 15 is heated 95 and maintained at a point slightly above 136° C. so that the titanium chloride is all kept 100

in a vaporous condition and is separated from the ferric chloride, which is a solid at this temperature. The chlorine is forced into the reaction retort 7, through the pipes 10, 5 under enough pressure (2 to 4 inches of water) to cause the titanium tetrachloride to pass through the filter partition 20, together with the excess of chlorine present and also the carbon monoxide and carbon dioxide 10 formed during the reaction of the chlorine upon the titanium dioxide and carbon. The receiver 31 for the condensed titanium tetrachloride is provided with a suitable water cooled condenser and the titanium tetrachloride is condensed therein and runs into the receiver as a liquid. A vent pipe 33 is provided on said receiver and a reflux condenser 34 is provided in said vent pipe to allow the escape of the unused chlorine and the 15 carbon monoxide and carbon dioxide, but not the titanium tetrachloride, any of which might tend to pass over, is condensed in the reflux condenser and returned to the receiver 31.

25 The operation of the apparatus in carrying out our process of making titanium tetrachloride from titanium dioxide, carbon and chlorine, may be briefly described as follows:

A charge of previously mixed and dried 30 crude titanium dioxide and carbon is placed in the retort 7, by removing the door 15^a, which is then bolted. Water is turned on to run through the condenser jackets 25 and 34. Gas burners 6 and 30 are lighted. The 35 retort 7 and its charge 37 is brought to a dull red heat at about 600° C. and dry chlorine is turned in through the pipes 10, 11, which percolates slowly through the charge 37. The chlorine acts on the titanium dioxide, 40 forming titanium tetrachloride and releasing oxygen which combines with the carbon in the charge forming carbon dioxide and carbon monoxide, the titanium tetrachloride being a vapor at 600° C. is carried out into expansion 45 chamber 15 with the excess chlorine, carbon monoxide and carbon dioxide and any ferric chloride which may be formed from the iron contained in the crude titanium dioxide used in the charge 37. Expansion chamber 15 is 50 maintained at a temperature of 136° C. which is the volatilization temperature of titanium tetrachloride. and the ferric chloride is deposited therein but the titanium tetrachloride remains in the gaseous phase mingled with the fine gas floated crystals of ferric chloride. These crystals of ferric chloride are separated from the titanium tetrachloride by means of filter plate 20. The titanium tetrachloride passes through and the ferric 55 chloride remains behind. Filter plate 20 and filter plate cover 22, are also kept at a temperature of 136° C. and the titanium tetrachloride being still in the gaseous phase passes into the condenser tube 24 and is cooled by 60 the water jacket 25, and in condensed form 65

runs into the receiver 31, from which it is drawn off through the cock 32. The unused chlorine mixture with carbon monoxide and carbon dioxide passes into the condenser tube 33, cooled by the water jacket 34, and any titanium tetrachloride not condensed in 24 is condensed in 33 and runs back to receiver 31. The unused chlorine mixed with carbon monoxide and carbon dioxide passes out of pipe 33 and may be further treated to recover 75 the unused chlorine.

After a charge has become exhausted in the retort 7, the door 15^a is opened and the residue in the retort 7 is scraped out into expansion chamber 15 and is removed with any ferric chloride which may have been deposited in the expansion chamber 15.

The filter plate 20 is made of filtros (a porous silica composition), porous carborundum or alundum or any other porous filtering medium which is resistant to chlorine, titanium tetrachloride, or iron chloride at 136° C.

We are aware that many changes in the general construction and arrangement of our apparatus as here shown for descriptive and illustrative purposes can be made and we do not, therefore, limit our invention to the details of the showing thus made, except as we may be limited by the hereto appended claims.

We claim:

1. In an apparatus for the purposes referred to, in combination, a retort, means for heating the same, an expansion chamber in communication therewith, means for heating the same, a heated filter diaphragm covering an outlet from said expansion chamber, a receiver connected with said expansion chamber outside of said filter diaphragm, means for cooling and condensing matter passing to said receiver, and a reflux condenser connected with said receiver, with means for cooling the same.

2. In an apparatus for the purposes referred to, in combination, a retort, means for heating the same to a desired temperature, means for introducing material to be acted upon to said retort, means for introducing a reaction gas into said material, means providing a closed expansion chamber with which said retort communicates with a sealed connection therebetween, means for heating said expansion chamber to a desired temperature, a condenser with which said expansion chamber connects, means interposed between said expansion chamber and said condenser for separating solid matter from gaseous product, and a receiver connected with said condenser to receive condensed product therefrom.

3. In an apparatus of the character referred to, a retort having one end closed, an expansion chamber with which the opposite end of said retort communicates with a sealed connection therebetween, a liquid receiver, a

condenser connecting said expansion chamber and said liquid receiver, with closed connections therebetween, and a filter means between said expansion chamber and said condenser.

5 Signed at Los Angeles, Los Angeles County, California, this 9th day of March, 1928.
